(57) **CLAIM**

The ornamental design for a latch closable container, as shown and described.

DESCRIPTION

FIG. 1 is a top perspective view of a latch closable container; FIG. 2 is a front view of the latch closable container of FIG. 1;

FIG. 3 is a right side view of the latch closable container of FIG. 1;

FIG. 4 is a back view of the latch closable container of FIG. 1; FIG. 5 is a plan view of the latch closable container of FIG. 1; FIG. 6 is a left side view of the latch closable container of FIG. 1;

FIG. 7 is a bottom view of the latch closable container of FIG. 1;

FIG. 8 is a plan view of the latch closable container of FIG. 1 when opened and with a tray inserted therein;

FIG. 9 is a top perspective view of the latch closable container of FIG. 1 when opened and with a tray inserted therein;

FIG. 10 is a bottom view of the latch closable container of FIG. 1 when opened;

FIG. 11 is a top perspective view of the latch closable container of FIG. 1 when opened and with the tray removed; and,

FIG. 12 is a second top perspective view of the latch closable container FIG. 1 when opened and with the tray removed.
